UNITED STATES PATENT OFFICE.

IRA EVERETT, OF ALLENTOWN, AND WILLIAM I. CANTLEY, OF BETHLEHEM, PENNSYLVANIA.

HOPPER CAR.

Application filed June 6, 1927. Serial No. 196,826.

The accompanying drawings illustrate the preferred form of the invention, though it is to be understood that the invention is not limited to the exact details of construction shown and described, as it is obvious that various modifications thereof within the scope of the claims will occur to persons skilled in the art.

In said drawings:

10 Figure 1 is a fragmentary top plan view of a hopper car constructed in accordance with this invention;

15 Fig. 2 is a view partly in side elevation and partly a vertical section taken on line 2—2 of Fig. 1;

Fig. 3 is a fragmentary top plan view of a modified construction of the structure shown in Fig. 1; and

20 Fig. 4 is a vertical section taken on the line 4—4 of Fig. 3.

This invention relates to hopper cars and it is an object of this invention to provide a hopper car of greater capacity without exceeding the permissible limits of width and height than has hitherto been possible and without adding to the length of the car. Hopper cars, as hitherto constructed, have been built to the limits of width and height and a greater capacity has been obtainable 30 only by lowering the floor or changing its slope, unless the length of the car be increased, to which changes there are serious objections. The objections to lowering the car floor have been overcome by this invention which permits of the slope sheets at the ends of the cars being placed lower without interfering with the wheels of the trucks and without necessitating changes in the slope of the sheets which will interfere with 40 the discharge of the car contents.

The hopper car, as shown in the drawing, comprises a body 1 mounted on trucks 2, the trucks being indicated diagrammatically by the wheels 3, shown in broken lines, which are mounted upon the axles 4. The body 1 is supported upon the trucks 2 in the usual manner by means of an underframe 6 of any suitable construction. To the underframe are secured the side posts 8 and end posts 50 10 which carry the side sheets 12 and ends 14, the side sheets 12 being tapered as usual in hopper cars and joined by end slope sheets 16 which extend below the underframe 6 and are fastened at their upper ends to the 55 ends 14. The slope sheets 16, together with

the ends 14, sides 12, hopper side sheets 18 and doors 20 form end hoppers from which the contents may be discharged in the usual manner by opening the doors 20, the doors being controlled by a suitable mechanism 60 (not shown).

In order that the car contents may be discharged freely, it is necessary that the slope of the slope sheet 16 be sufficient to cause the contents to travel thereon by gravity and 65 that it be without obstructions which will impede the progress of the contents along the sheet. To permit of the lowering of the sheet 16 and thereby increase the distance from the sheet 16 to the top of the car and 70 thus increase the capacity of the car, openings 22 of greater length than the wheel diameter are formed in the slope sheets 16 so as to permit the slope sheets to be set closer to the inner wheels 3 of the trucks, 75 and at the same time to provide the necessary clearance for the movements of the wheels. The openings 22 are closed by wheel hoods 24 which, as shown in Figs. 1 and 2, are formed integral with the slope sheets 80 16 by pressing the hoods in the sheets.

Each wheel hood 24 is formed with an inclined substantially flat upper surface 26 which extends for the greater part of the length of the hood and which forms an acute 85 angle with the plane of the slope sheet and increases in width slightly from where it merges with the slope sheet to its lower edge where it is at its greatest distance from the slope sheet and where it is over the inner 90 portion of the wheel 3. The lower edge of the flat upper surface 26 is joined by a curved end surface 28 to the slope sheet 16 and the sides of the upper surface 26 and end surface 28 are joined to the slope sheet 95 16 by the flaring tapering sides 30, the end surface 28 being at a greater angle to the slope sheet than the flat upper surface 26. It will be noted that this design of wheel hood provides an opening of sufficient size 100 for movements of the wheel 3 and yet provides a cover for the wheel which will in no way interfere with the discharge of the contents from the car, the slope of the upper surface 26 of the hood being such that the 105 contents will travel therealong under the influence of gravity, and the tapering of the upper surface 26 and the flaring of the sides 30 of the hood providing for the passage 110 of the contents of the car to the sides of

- the hood without material interference therewith.
- In the modified construction shown in Figs. 3 and 4, the slope sheet 16 is provided with an opening 40 for the wheel 3, the opening being closed by a wheel hood 42 which is formed of a separate pressed member having a substantially flat upper surface 44, which extends for the greater portion of the length of the hood, and a curved end surface 46 which extends to the slope sheet 16, and along the sides of the surfaces 44 and 46 the hood is formed with perpendicular sides 48 provided with outwardly projecting flanges 50 by means of which the hood is secured to the slope sheet 16 by the rivets 52. In this construction, as in the construction shown in Figs. 1 and 2, the upper surface 44 makes an acute angle with the slope sheet 16 and extends downwardly to a point beyond the inner axle 4 where it is of greatest height above the slope sheet and from which point the curved end 46 extends to the slope sheet, the curved end making a greater angle with the slope sheet than does the flat upper surface 44. In this construction, as in the other, the slope of the flat upper surface 44 is sufficient to permit the contents of the car to be moved by gravity therealong and the upper end of this surface is tapered so as to offer a minimum of resistance to the movement of the contents of the car along the slope sheet.

What is claimed is:

- 35 1. In a hopper car, an end slope sheet having a wheel hood therein, said hood being of greater length than the wheel diameter and having its greatest height above the slope sheet adjacent its lower end.
- 40 2. In a hopper car, an end slope sheet

having a wheel hood thereon, said hood having a substantially flat upper surface extending for the greater portion of its length and forming an acute angle with the slope sheet and an end surface connecting the raised end of the flat upper surface with the slope sheet.

3. In a hopper car, an end slope sheet having a wheel hood thereon, said hood being of greater length than the wheel diameter and having a flat upper surface extending for the greater portion of its length at an angle to the slope sheet and an end surface connecting the raised end of the flat upper surface with the slope sheet.

4. In a hopper car, an end slope sheet having a wheel hood thereon, said hood having a flat upper surface inclined downwardly and extending at an acute angle from the slope sheet to a point beyond the inner wheel axle, and an end surface connecting said flat upper surface with the slope sheet, said end surface being of less length than the flat upper surface and extending at a greater angle to the slope sheet.

5. In a hopper car, an end slope sheet having a wheel hood thereon, said hood being of greater length than the wheel diameter and having a substantially flat upper surface forming an angle with the slope sheet and extending to the point of greatest height above the slope sheet at a point beyond the inner axle and a curved end surface connecting the raised end of the flat upper surface with the slope sheet.

In witness whereof we have hereunto set our hands.

IRA EVERETT.
WILLIAM I. CANTLEY.
